UNITED STATES PATENT OFFICE

WILLIAM J. WOOLLEY, OF CHICAGO, ILLINOIS

WATER CLOSET

Application filed March 14, 1939. Serial No. 346,906.

My invention relates in general to water closet tanks and flushing devices and has for its object broadly the provision of a tank and inlet valve therefor of silent operation.

5 Primarily the invention contemplates the provision of an improved automatically controlled water closet tank inlet valve wherein provision is made for its silent operation, and wherewith is provided means for regulating and shutting off the water supplied to the valve.

10 Prior to my invention considerable annoyance has been experienced by reason of noise occurring in the inlet valve casing upon flushing of the closet bowl, this noise being due largely to the accumulation of pockets of air in the inlet valve casing and around the valve after the flushing operation.

The main object of the invention is the 15 provision of simple and effective means which provides for the silent operation of the automatically controlled inlet valve while the tank is being refilled as an incident to the flushing and refilling of the closet bowl.

20 Another important object of the invention is the provision of simple means which effectively provide against air accumulating and mixing with the water around the inlet valve disposed in an inner chamber provided in the 25 automatically controlled inlet valve casing.

A further object of the invention is the provision of a water supply regulating and shut-off valve to be associated with the automatically controlled inlet valve for the purpose of 30 regulating the water supplied through the inlet valve.

35 A further object of the invention is the provision of a water supply regulating and shut-off valve which provides means for shutting off the water to make repairs in the inlet valve.

40 A further object of the invention is the provision of a water supply regulating and shut-off valve and an automatically controlled inlet valve which may be readily associated or disassociated with each other without disturbing the internal parts of either valve.

45 A further object of the invention is the provision of simple means which provides for readily joining the assembled automatically

controlled inlet valve and the assembled regulating and shut-off valve in cooperative relation with each other, either before shipment from the factory at which they are made or at the place of their installation.

55 Another object of the invention is the provision of an automatically controlled inlet valve enclosed in a casing which is provided with an inner and outer chamber and which casing forms an enclosure for a portion of the valve operating mechanism which is hingeably secured therein.

60 Numerous other objects and advantages of the invention will be apparent as it is better understood from the following description, which, taken in connection with the accompanying drawings, discloses a preferred embodiment thereof.

65 Referring to the drawings:

70 Figure 1 is a transverse vertical sectional view taken through a tank embodying my invention;

75 Fig. 2 is a longitudinal vertical sectional view showing the improvements as embodied in my invention, and

80 Fig. 3 is a perspective view of a tube or silencer sleeve which forms one of the improvements as embodied in my invention.

85 For the purpose of illustrating my invention, I have shown it embodied in a tank 11 of ordinary or preferred construction, the one shown on the drawings being of the type termed in the trade "low down". This tank is adapted to communicate in any suitable manner with a closet bowl (not shown) through a pipe 12 suitably connected through the bottom of the tank by means of fittings 13 and 14, the fitting 14 providing a seat for a discharge valve 15 which provides a seal between the tank and the water closet bowl. The valve 15 may be moved by any suitable means to establish communication between the pipe 12 and the interior of the tank to flush the bowl. Water is admitted to the tank through a supply pipe 16 which communicates with the main supply pipe 17 which is attached to the bottom of the tank in the usual manner, as indicated at 18. The upper end of pipe 16 is threaded, as indicated at 22, into a casing 19 which is provided with

86 90 94 98 102

a regulating and shut-off valve 21. The casing 19, as constructed in the present instance, is provided with two opposite open ends 23 and 24, the end 23 being threaded at 25, and 5 the end 24 at 26 and 27. Intermediate the ends, the casing provides a central chamber 28 above a valve seat 29 for the regulating and shut-off valve 21.

The casing 19 is also provided with a lateral threaded opening 31 communicating with the central chamber 28. The valve 21 extends through the opening 27 and has threaded engagement with threads 26, said valve 21 being provided at its outer end with 15 a screw-driver slot 32 as a means for adjusting same to a suitable position. A packing nut 34 is engaged with threads 27 and compresses packing 33 to prevent leakage around the valve 21.

20 The automatically controlled valve, generally indicated as 35, comprises, in the present construction, a valve casing 36 which encloses a longitudinally movable valve 37 and a portion of the valve operating mechanism 38, the valve 37 being provided with a guiding member 39 which is slidably mounted in the casing 36, and through the guiding member 39 is formed a slot 41 which is arranged in cooperative relation with a slot 42 provided in the casing 36, as indicated in Fig. 2, said valve operating portion 38 being inserted through the slots 41 and 42 and hingeably secured by a pin 43 in the hollow lug 44, as indicated in Fig. 2.

35 Between said valve 37 and its guiding member 39 is disposed a cup-shaped member valve 45 slidably mounted in the casing 36 but adapted to prevent leakage of water from the casing through the slot 42. Through an opening 46 in the end of said casing 36 is inserted a silencer sleeve 47 which is adapted to form an inner chamber 48 and an outer chamber 49 in combination with the casing 36. An opening 51 is provided in the side of the sleeve 47 and arranged upwardly when the sleeve is inserted in the casing 36, the opening 51 providing a passage for water from the inner chamber to the outer chamber. Fitted into the open end of the sleeve 47 is a flange union 52 which has a threaded opening 53 into which is threaded a tubular valve seat 54, the cup shaped washer 45 and the casing 36 being adapted to form a closure for one end of the inner chamber 48, and the union 52, valve seat 54 and valve 37 being adapted to form a closure for the opposite end of said chamber. The inner chamber thus formed provides for the maintaining of a water seal 58 around the valve 37 during the operation of opening and closing same when flushing the closet bowl and filling the tank 11, said water seal being permanent, prevents the accumulation of air around the valve at all 65 times. From certain aspects of this inven-

tion, the sleeve 47 may be considered a casing part and the opening 51 its outlet opening.

The union 52 is clamped, together with a packing 55, against the end of the casing 36 by means of a clamping nut 56 which is threaded over the external threads 57 of the casing 36. The outer end of the union 52 is provided with external threads 58 which are adapted to fit the threaded opening 31 of the casing 19.

70 The casing 36, as constructed in the present instance, provides a downwardly projecting chamber 59, which joins with the outer chamber 49, and into the bottom of the chamber 59 is threaded an outlet or delivery pipe 61, the upper end of which extends into the chamber 59 an appreciable distance above the bottom 62 thereof, so that the chamber 59 cannot be completely drained.

75 An overflow pipe 63 is provided to determine and limit the height of the water in the tank, and the bottom end of this pipe being threaded into the hollow fitting 14 forms an overflow outlet for the tank 11.

80 A refill pipe 64 is threaded into the casing forming the chamber 59 at or near its bottom 62 and below the top of the delivery pipe 61 and, from its connection with the casing, as shown at 65, it extends upwardly terminating into a loop or bend 66, the end of which extends into the top of the overflow pipe 63 through which it is in communication with the hollow fitting 14 and consequently with the closet bowl when the tank 11 is installed. The space beneath the top 85 of the delivery pipe 61 and the bottom of the chamber 59 forms a water seal covering the lower end of the pipe 64, and this seal prevents the entrance of air into the receiving end of the refill pipe at all times.

90 When the valve 15 is open to flush the bowl, the water runs rapidly from the tank and lowers the float 67, which, being mechanically connected to the valve operating lever 38, opens the valve 37, admitting the 95 supply water from the pipe 16. The inner chamber is already full of water and stays so after the valve 37 closes, so that this valve is always immersed and there is no opportunity for the formation of air pockets or 100 for audible vibration in any of the valve positions.

105 It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

110 I claim:

115 1. A closet tank inlet valve comprising a horizontally arranged valve casing, a valve

in said casing, and a sleeve embracing said valve and having an opening providing a water seal about said valve.

2. A closet tank inlet valve comprising a horizontally arranged valve casing, a valve in said casing, and a sleeve surrounding said valve and having an opening in its top for providing a water seal about said valve.

WILLIAM J. WOOLLEY.
